UNITED STATES PATENT OFFICE

162,774

SOCK

Arsene Beauchemin, Montreal, Quebec, Canada

Application July 8, 1950, Serial No. 11,029

Term of patent 7 years

(Cl. D47—7)

To all whom it may concern:

Be it known that I, Arsene Beauchemin, a Canadian citizen, residing at 4862 St. Denis Street, Apartment 13, city of Montreal, Province of Quebec, Canada, have invented a new, original, and ornamental Design for a Sock, of which the following is a specification, reference being had to the accompanying drawing, forming part thereof, wherein the single figure is a perspective view of a sock, showing my new design.

I claim:

The ornamental design for a sock, as shown.
ARSENE BEAUCHEMIN.
